UNITED STATES PATENT OFFICE.

ROBERT MILNE, OF ROCKFORD, ILLINOIS, ASSIGNOR TO WARD PUMP COMPANY, OF ROCKFORD, ILLINOIS, A CORPORATION OF ILLINOIS.

APPARATUS FOR MAKING CUP-LEATHERS.

1,288,111.

Specification of Letters Patent.

Patented Dec. 17, 1918.

Application filed July 26, 1916. Serial No. 111,463.

To all whom it may concern:

Be it known that I, ROBERT MILNE, a citizen of the United States, residing at Rockford, in the county of Winnebago and State of Illinois, have invented certain new and useful Improvements in Apparatus for Making Cup-Leathers, of which the following is a specification.

This invention relates to the manufacture of cup leathers that are employed as piston packing in pumps, and has more particular reference to the manufacture of cup leathers by means of automatic machines such as are described in the Collins and Trostle Patent No. 1,183,956 and Milne Patent No. 1,184,004.

These machines will automatically form a blank of leather into cup shape by a spinning and pressing process, and my present invention is designed for use in connection with machines of this character and especially with that described in the Milne patent, which is particularly adapted for forming relatively large size cup leathers, which are more difficult to manufacture than the smaller sizes.

It has been found that, because of variations in the quality and character of the fibers of ordinary commercial leather, due to the different processes of curing and also to location in the hide, the leather blanks when formed into cup shape by the automatic forming machine mentioned are not all uniform, that is, they do not all retain a perfect cup shape after leaving the machine since those of certain quality have a tendency to flare out slightly. This objection may be remedied in some cases by lengthening the time of working and forming the cup leather in the machine so as to insure perfect driving and setting by the spinning and heating operation. But since this is not necessary for many blanks the increased time of making each cup leather unnecessarily reduces the productiveness per time unit of the machine.

The primary object of my invention is to provide means for increasing the productiveness of automatic cup leather manufacturing apparatus and for securing well formed

and uniform cup leathers regardless of variations in the fibers of the leather.

Another object of my invention is to provide apparatus for manufacturing cup leathers, consisting of a machine for forming a blank of leather into cup shape, preferably by a spinning and pressing process, and a machine for resetting and fixing the cup leather in the desired shape after it has been removed from the forming machine. In accordance with my invention, cup leathers delivered from the forming machine in a somewhat flared and non-uniform shape will be refixed in the desired shape by a simple compressing and forming process in the second machine. In other words, all cup leathers after being formed from a blank in one machine are immediately put into a reshaping machine which recompresses and sets the cup leather into the desired shape. This second machine which constitutes a finishing machine permits the first machine to be speeded up so that the time required for forming each blank into cup shape is reduced to a minimum and those cup leathers which are not fully and perfectly formed in the first machine are positively fixed in shape and finished by the second machine.

A further object is to provide in combination with an automatic machine for making cup leathers, a machine for reshaping and forming cup leathers that is automatically operated in timed relation with the first machine, so that the apparatus may turn out a larger number of uniform cup leathers per hour than has been heretofore possible with only a forming machine. It follows that apparatus of this character reduces the cost of producing cup leathers.

Further objects reside in various features of construction and arrangement of the reshaping machine which together with the attending advantages thereof will be fully understood by reference to the following description when considered in connection with the following drawings, in which—

Figure 1 is a front elevation of a cup leather forming machine combined with my improved reshaping machine;

Fig. 2 is a fragmentary view looking at a portion of the left hand side of the forming machine shown in Fig. 1, of the cam connection between the forming and reshaping machines;

5 Fig. 3 is an enlarged front elevation of my improved reshaping machine;

Fig. 4 is a sectional view taken on the line 4—4 of Fig. 3;

10 Fig. 5 is a fragmentary sectional view taken on the line 5—5 of Fig. 4;

Fig. 6 is a rear elevation of the machine;

15 Fig. 7 is a fragmentary view in elevation looking at the right hand side of the machine as shown in Fig. 6;

Fig. 8 is a plan sectional view taken substantially on the line 8—8 of Fig. 3; and

19 Fig. 9 is an enlarged vertical sectional view taken on the line 9—9 of Fig. 8.

20 In this invention I have provided, generally stated, apparatus for manufacturing cup leathers comprising means for automatically forming a cup leather from a blank and means for reshaping the formed cup leather. In illustrating the apparatus on the drawings, I have shown but a single view of a machine for automatically forming cup leathers, this machine being fully shown and described in my Patent No. 1,184,004, mentioned above. It should be understood, however, that my improvements contemplate the use of any machine for forming a blank of leather into cup shape in connection with certain improvements described hereinafter whereby to secure the objects prefaced above.

25 The forming machine designated generally by reference character 11, is adapted to automatically form a blank of leather into cup shape by a spinning and pressing process, bevel the edge of the cup, true, polish the outer face thereof, and set the fibers in cup shape by a compressing and frictional heating process as is fully described in the said Milne patent. In performing these 30 steps, the rotary male or compressing die 12 co-operates with a female die or cup leather holder contained within the table 13. Since the machine is automatically and continuously operated, an equal amount of time is 35 spent in forming each blank into cup shape but because of variations in the fibers of the leather some blanks should be worked longer than others to insure that they will retain the desired cup shape after leaving 40 the machine. Since blanks requiring longer operation are comparatively few in number and not hardly detectable before commencing the forming operation, it is not feasible to set the machine to operate on each blank 45 the maximum period of time demanded by the exceptionally obdurate blanks as this would materially decrease the productiveness of the machine and correspondingly increase the cost of production.

I have found that by tempering the 65 blanks to a minimum extent, setting the forming machine to operate on each blank a minimum length of time and then reshaping the cup leathers after removal from the forming machine, not only a material reduction in cost of manufacture is obtained 70 but the cup leathers after removal from the second machine are uniform in every respect and will retain their shape. This reshaping machine is operated in timed relation with 75 a forming machine so that they work in synchronism and one operator may easily attend to the operation of both.

The construction and operation of the reshaping machine is as follows: A suitable 80 base 14, supported in this instance by three legs 15 arranged in triangular relation, carries a rotatably mounted table designated generally by reference character 16 and a pair of upright side columns 17 disposed at 85 the front of the machine and overhanging a marginal portion of the rotary table. The table 16 supported in spaced relation above the base 14 by a central support and bearing 18 and a marginal support 19, the latter being disposed intermediate the columns 17, has fixedly secured thereto a pivot bolt 21 loosely journaled in the bearing 18, as shown in Fig. 7, and is provided on its upper face with an integral toothed face 22 with which 90 a correspondingly toothed element 23 loosely mounted on the bolt 21 co-operates. By this means a ratchet driving connection is established between the table 16 and the member 23, which is the driving element of the clutch 100 and is shaped to provide a segmental gear 24 that meshes with a rack 25 slidably mounted in a horizontally disposed frame extension 26 rigidly secured to one of the side columns 17. A contractile spring 27 connecting one 105 end of the rack 25 to the outer end of the extension 26 constantly urges the ratchet member 23 in a counterclockwise direction, viewing Fig. 8. The rack may be moved against the tension of the spring 27 to rotate 110 the clutch member 23 and rotate the table in a clockwise direction, viewing Fig. 8, by means hereinafter described, it being desirable to rotate the table intermittently in equi-distant movements, that is, in step by 115 step movements to different stations.

Referring to Figs. 8 and 9, it will be observed that the table is provided in its top face with a plurality of cylindrical sockets 12 28 which constitute cup or female dies. At the bottom of each socket is disposed a disk 29 having a slightly conical upper face as shown in Fig. 9 and a depending shank 31 slidably fitting in a bearing 32 in the table and projecting beneath the depending 12 1 boss of the bearing. These seat members 29 normally rest on the bottoms of the sockets as shown in Fig. 9 but may be raised to a

position in which their cone faces are substantially flush with the top of the table. This raising of the members 29 is effected by a stationary inclined cam 33 secured to the bed 14 and arranged at one side of the machine in the path of the depending ends of the shanks 31, so as to elevate each seat member 29 as its shank is moved over the cam by rotation of the table and to lower the seat member by a reverse incline before the cup receiver in which the seat is located has reached a loading station, which is in this instance intermediate the columns 17.

The cup dies 28 are each adapted to receive at the loading station a cup leather pressed into the die by the male or plunger die as will be presently described. A cup leather is pressed into the die at this point with considerable pressure, so that the dies compress and very positively set the cup leather in its desired shape. Upon withdrawal of the plunger die, leaving the cup leather in the female die, the table will be rotated in step by step movements bringing the remaining cup receiving dies successively to the loading station, so that during the interval that the cup leather is being carried away from the loading station and until it is ejected from the die by raising of the disk seat 29, it had had sufficient time to become fixed in a desired shape by a drying process. This drying may be accomplished by a natural drying action or through some heating medium contained within the table. For this purpose the table is of a hollow construction and adapted to contain hot water or an electric heater.

The male or plunger die, designated generally by reference character 34, secured to the lower end of the plunger 35 slidably mounted in bearings 36 interposed between and bolted to the columns 17, is connected by means of a pitman 37 to a crank shaft 38 journaled in the bearings 39 on the upper end of the column 17. Suitable means may be provided for rotating the crank shaft intermittently in single revolution movements whereby to reciprocate the male die in pressing and retracting strokes. Any suitable clutch driving means may be employed for rotating the crank shaft 38, and in the present instance I have illustrated somewhat briefly a clutch drive commonly used in punch presses and similar machines. It consists of a drive pulley 41 loosely mounted on the crank shaft 38 and adapted to be fixedly connected thereto by means of a dog 42 slidably mounted to move axially of the shaft 38 in a collar 43 fixed to the shaft at the outer end of one of the bearings 39, the dog being constantly urged by a spring (not shown) into engagement with a toothed internal face on the pulley 41 as is well understood in clutches of this character. The

dog 42 is normally held out of driving engagement with the pulley 41 by means of a lever 44 pivoted at 45 to the standard 17 and provided with a beveled end 46 that is held by means of a contractile spring 47 in an annular groove 48 in the collar 43, as shown in Figs. 4 and 5. When the beveled end of the lever is swung downwardly out of the groove 48 so as to withdraw its engaging end from the portion 49 of the dog 42 that extends into the annular way 48, the dog will be moved by its spring into engagement with the pulley 41, thus connecting the crank shaft to the pulley so that the two rotate together. Upon releasing the lever 44, the spring 47 will return the lever into position in the annular way 48 so that the projecting dog portion 49 will engage the inclined bevel 46 and be moved thereby out of engagement with the pulley 41, thus breaking the driving connection. The clutch driving device may be of suitable design and is operated by the forming machine mentioned in the early part of the specification. Referring to Figs. 1 to 4 inclusive, it will be seen that a connection is established between the main cam shaft 51 of the forming machine and the lever 44, comprising a lever 52 pivotally mounted intermediate its ends on the frame of the forming machine and adapted to be actuated at one end by a cam 53 on the main cam shaft and pivotally connected at its opposite end with the lever 44 through the intermediary of a link 54, lever 55 fixed to a leg 15 of the reshaping machine, link 56, lever 57 and link 58, which in turn is connected to the lever 44. This connection might be established directly between the drive clutch and cam shaft 51 but the present arrangement is suitable for the two machines when placed relatively as shown in the drawings. By reason of this connection, the shaping machine will be put into operation at predetermined intervals by and in timed relation with the forming machine, which operation will be described more particularly hereinafter.

Referring to Fig. 3, a stop rod 59 slidably mounted in bearings 61 integral with one of the columns 17 is adapted to project at its lower end into the path of the blocks 62 fixed to the top of the table 16, so as to prevent rotation of the table in a clockwise direction, viewing Fig. 8, when a cup-receiving die has been moved into alignment with the compressing head. A pin 63 on the upper end of the rod 59 limits the lowering movement thereof and the rod may be raised from stopping position by a lever 64 pivoted to the adjacent column 17, and disposed between a roller and pin mounted on the rod 59. The outer end 65 of the lever 64 is adapted to be raised by the raising action of the plunger 35, and for this purpose a

finger 66 pivoted to a collar 67 secured to the plunger 35 is prevented by a stop 68 against pivoting in a counterclockwise direction viewing Fig. 3, and urged by a spring 69 against said stop. This finger 66 is adapted to spring out of the path of the end 65 upon lowering movement of the plunger and to engage the said end 65 upon initial upward movement of the plunger so as to quickly raise the rod 59 from engagement with the adjacent block 62.

During the balance of the raising movement of the plunger after the male die has cleared the top of the table the plunger is employed to rotate the table in the following manner. Referring to Fig. 6, a rod 71 slidably mounted in bearings 72 secured to the adjacent column 17 is connected at its lower end to the rack 25 through the intermediary of a chain 73 engaging a guide pulley 74 mounted on the inner end of the frame extension 26. The collar 67 on the plunger 35 is provided with an extension 75 embracing the rod 71 upon which extension a collar 76 loosely mounted on the rod is held seated by an expansion spring 77 that is interposed between the said collar 76 and collar 78 fixed to the rod. Under the influence of the contractile spring 27 the connection between the rack 25 and the rod 71 is held taut, since the said spring holds the collar 76 seated on the extension 75. Upon lowering movement of the plunger the table clutch element 23 will be slipped backwardly over several notches by the influence of the spring 27, this movement being limited by the lowering movement of the extension 75. Upon raising the plunger the said extension 75 acting through the resilient connection 25 between the same and the rod 71 and the clutch connection between the rack and table will rotate the latter a distance to move a new cup receiving die to the loading station, it being obvious that during such raising movement of the plunger the finger 66 becomes disengaged from the lever 64, permitting the stop rod 59 to drop into position to stop the table. With regard to the connections just described, it should be understood that I do not limit myself to the particular mechanical expedients shown for effecting the several steps since various other means might be equally well employed.

Referring now to Fig. 9, the compressing head 34 consists in general of two members, viz: a head supporting member secured to the plunger 35 and a head slidably mounted on the said supporting member. The supporting member may consist of a body 79 having an externally threaded extension 81 threaded into a socket in the end of the plunger 35 and being provided with a depending annular flange or guideway 82. The head consists of a block 83 slidably

mounted within the flange 82 carrying a 65 diametrically extending pin 84, the ends of which project through axially extending slots 85 in the flange 82 and are secured to a sleeve 86 slidably mounted on the outer wall of the said flange 82. An expansion 70 spring 87 interposed between the plunger 35 and block 83 constantly urges the head 75 downwardly to a position limited by abutment of the pin against the lower ends of the slots 85. A ring 88 having a bevel 75 underface and a lock nut 89 are threaded onto the upper end of the sleeve member 86. The head just described constitutes a male die of which the peripheral wall of the sleeve 86 is adapted to shape the inner wall 80 of a cup leather and the beveled face of the ring 88 to engage the bevel of the cup and serve as a means for axially compressing the flange of the cup leather so as to effectively set the fibers in the cup shape. The 85 underfaces of the members 82, 83 and 86 are shaped to conform to the slightly conical face of the disk seat 29 so that the center of the cup leather will be dished inwardly to produce a somewhat acute angle at the corner of the cup which tends to better secure the cup in the desired shape. An annular knife 91 fixedly secured to the periphery of the block 83 projects beneath the same a distance slightly greater than the thickness 95 of a cup leather so as to cut out the center thereof when the compressing head is forced to its lowermost position, the top of the disk 29 having a suitable soft metal face so as not to blunt the edge of the knife. 100

A centering device is employed for holding a cup leather in position at the loading station so that the compressing head or die in its descent will properly engage the cup leather. This centering device consists of 105 a centrally apertured disk 92 disposed in close proximity to the table in alignment with the plunger and rigidly supported from the side columns 17. A bushing 93 secured in the aperture of the disk 92 is 110 beveled at its upper end so as to provide a tapered mouth or seat adapted to receive a cup leather. A cup leather placed on this seat will assume a central position with respect to the die even though the wall of 115 the cup leather is somewhat flared. By supporting a cup leather in this manner, it is so positioned that the compressing head will properly engage it to insure that the cup leather will be evenly forced into the female 120 die. The centering disk 92 also serves to strip a cup leather from the plunger die in the event that the cup leather sticks to the die on the return stroke thereof.

When a cup leather has been carried by 12 the table from the loading station to the point where it is ejected from the female die by the action of the cam 33, the cup leather

will be automatically discharged from the table into a container. Referring to Figs. 6 and 8, this discharging means consists of an arm 94 pivotally mounted at 95 and arranged so that when the table is at rest with a cup leather raised to the top of the table, the cup leather will be disposed in close proximity to the arm 94, which when swung outwardly in a quick movement, will throw the cup leather from the table into a suitable container 96. This movement of the arm 94 is automatically effected by movement of the block 62 adjacent to the cup leather to be discharged, which block will, upon initial movement of the table, actuate a roller equipped arm 97 disposed in its path and rigidly connected to the arm 94 so as to swing the same outwardly. A contractile spring 98 connected with the upper end of the pivot bolt 95 will return the arm 94 to normal position which is limited by abutment of the said arm 94 against a stop 99 depending from the frame extension 26.

The operation of my improvements is as follows: The forming machine 11 being put into operation will, as described in my patent mentioned above, form a blank of leather into cup shape and will automatically repeat this operation, allowing an interval of time between each forming operation without stopping the machine, sufficient to remove the formed cup from the machine and place a new blank thereon. A formed blank removed from the machine is immediately placed by the operator on the centering holder 92, and shortly thereafter the cam 53 of the forming machine will automatically cause the drive pulley 41 (which is constantly driven) to be connected to the crank shaft 38 through the intermediary of the link and lever connections and clutch connection described above. The crank shaft will be rotated one revolution during which the compressing head will be lowered and raised, whereupon the crank will be automatically stopped by disengagement of the dog 42 from the drive wheel as described. As the plunger descends, the sleeve 86 of the male die will enter within the flange of the cup leather and force the same down through the bushing 93 and into the female die to the position shown in dotted lines in Fig. 9. The final downward movement of the plunger will impose considerable pressure on the cup leather so as to compress the same very tightly between the walls of the dies and thus reset the fibers of the leather. Simultaneously with this setting or shaping action, the knife 91 is forced through the cup leather cutting out a central aperture therein, which completes the shaping of a cup leather. It will be noted that by reason of the resiliently yieldable mounting of the male die the pressure brought to bear on the cup leather will be no greater than the pressure of the spring 87. Because of this resilient action of the male die, there is no possibility of injuring the fibers of the leather, and also, the cutting action of the knife 91 is easily effected regardless of slight variations in thickness of the leather. The force of the plunger in its compressing stroke as brought to bear upon the table, is resisted by the brace or support 19 disposed directly beneath the plunger. Upon raising the plunger the male die withdraws from the cup leather leaving the same in the female die. During the initial raising movement of the plunger the stop bar 59 will be withdrawn from the adjacent block 62 and at a slight interval thereafter, when the lower edge of the male die has been raised above the top of the table, the same will be automatically indexed, that is, moved in a clockwise direction, to carry the next succeeding female die to the loading station, this indexing being effected through means of the parts 23, 25, 67, 71 and 73 as described above. The stop rod 59 will drop into stopping position immediately after the stop block has been carried from beneath the rod, and the spring 27 will retract the clutch element 23 several notches so that upon the next actuation of the plunger the table will be again indexed. The cup leather just described remains in the female die until the same is carried in step by step movements to the discharge station and while in the die the cup leather will become further set in position by reason of its being held therein by the walls of the die and of the drying action by exposure to air and also by the action of the heating medium within the table if such is desired. The manner of automatically discharging the cup leather from the table has been described above, and it will be noted that a cup leather is discharged at each indexing movement of the table.

From the foregoing, it will be manifest that by combining a forming and reshaping machine in the manufacture of cup leathers, a material saving is effected in the time required for manufacturing a given number of these articles, and the resultant articles are uniform and complete in every respect requiring no further working or treatment. The machines being automatically operated require little or no attention on the part of an operator, his attention being only required to supply blanks of leather to the forming machine and to transfer the formed blanks therefrom to the reshaping machine. It will be noted that the reshaping is effected mainly by a simple compressing action in which the cup leather is forcibly confined between the walls of die members and that

the cup leather is ejected from the die without liability of flaring or deranging the cup leather as might occur in removing or withdrawal of the revolving female die from the cup leather in the forming machine.

It is believed that this conveys a clear understanding of my invention and accomplishes the objects prefaced above, and it should be understood that while I have shown for purpose of illustration but a single embodiment of the invention various modifications and changes in details of construction may be resorted to without departing from the spirit and scope of the invention or sacrificing any of its material advantages.

I claim:

1. In apparatus for making cup leathers, the combination of a rotary table provided with a plurality of circumferentially spaced cup dies, a reciprocable plunger die disposed at a loading station and adapted to press a cup leather into a cup die, stationary means for supporting a cup leather at the loading station interposed between the plunger die and cup die so that the cup leather will be pressed by the plunger die into the cup die, and means for rotating the table in step by step movements to move the cup dies in succession to the loading station.

2. A machine for reshaping cup leathers, comprising a rotary table provided with a plurality of cup dies adapted to be moved in succession by rotation of the table to a loading station, a reciprocable plunger adapted to press a cup leather into a cup die at the loading station, a stationary cup leather support at the loading station adapted to hold and center a cup leather above a cup die in the path of the plunger so that the cup leather will be centrally engaged thereby and pressed into a cup die, and means for rotating the table to move the next succeeding cup die to the loading station after the plunger has been withdrawn leaving the formed cup leather in the preceding cup die.

3. A power operated cup forming machine, said machine being constructed and arranged to form blanks of leather into cup shape with a dwell between successive cup forming operations sufficient to permit an operative to remove a shaped blank from and insert a new blank in the machine and place the shaped blank in a reshaping machine, in combination with a power operated machine adapted to reshape the cups formed by the cup forming machine with a dwell between successive reshaping operations sufficient to permit an operative to place a cup

from the cup forming machine in the reshaping machine, the operation of the reshaping machine being controlled by the operation of the cup forming machine in such manner that the dwells between successive reshaping operations will occur simultaneously with the dwells between successive cup forming operations.

4. The combination with a power operated machine for forming leather blanks into cup leathers, of a series of cup dies adapted to each receive a cup leather after it has been formed by said forming machine, a compressing die disposed at a loading station and adapted to press a formed cup leather into a cup die, and means controlled by the cup forming machine for successively operating the compressing die and moving a cup die away from the loading station and another to the same during the time that the cup forming machine is operating to form a cup from a blank.

5. The combination of a power operated machine for forming blanks into cup shape, a machine for reshaping the cups formed by the cup forming machine, and means controlling the operation of the reshaping machine by the operation of the cup forming machine so that during the interval between successive shaping operations of the cup forming machine an operative may take a shaped cup from the forming machine and place it immediately in the reshaping machine, the latter machine being inoperative during such interval and operated to reshape the cup while the forming machine is operating to form another cup from a blank.

6. In a machine for reshaping cup leathers, the combination of a cup die adapted to receive a formed cup leather, and a compressing die adapted to compress a cup in the cup die comprising a plunger body, a head forming the compressing die element and mounted on the plunger so as to be movable axially thereupon, and means yielding urging the die element axially in one direction so that the compressing action of the plunger body will be transmitted to the compressing die in the compressing action through the agency of said yielding means.

7. In a machine for forming cup leathers, the combination of a cup die, a compressing die adapted to enter the cup die for shaping a cup leather therein, and means interposed between the cup die and compressing die for holding a cup leather over the cup die in position to be engaged by the compressing die and serving also as a stripper when the compressing die is withdrawn.

ROBERT MILNE.
